UNITED STATES PATENT OFFICE.

CHAUNCEY W. GAY, OF WEST SPRINGFIELD, MASSACHUSETTS.

PAPER-BOX MACHINE.

SPECIFICATION forming part of Letters Patent No. 773,318, dated October 25, 1904.

Application filed March 16, 1904. Serial No. 198,458. (No model.)

To all whom it may concern:

Be it known that I, CHAUNCEY W. GAY, a citizen of the United States of America, and a resident of West Springfield, in the county of 5 Hampden and State of Massachusetts, have invented certain new and useful Improvements in Paper-Box Machines, of which the following is a full, clear, and exact description.

This invention relates to machines for folding longitudinally-scored blanks of cardboard or similar material, said blanks being supplied with a deposit of gum to retain the opposite sides of the blank together, and thus from what may be termed "cartons," which are 15 collapsed and may be stacked into piles ready for shipment; and my invention has for one of its objects the provision of an improved machine in which the blanks to be folded are placed in a pile at one end thereof and consecutively fed to the gumming and folding mechanism, which includes means for compressing the folded blank to cause a thorough union between the gummed portions of the blank, and in which the folded blanks are finally 25 stacked for transportation.

My invention has, furthermore, for its object the provision of a blank-receiving device capable of storing a vastly-greater supply than heretofore and without interfering with 30 the removal of the bottom blank on account of undue or excessive friction caused by the weight of such additional blanks.

My invention has, furthermore, for its object the improved construction and organization 35 of the blades around which the sides of the blank are folded to form the carton, these blades being stationary while the blanks are consecutively brought into proper position longitudinally thereon by one or more conveyors and held against longitudinal movement therewith by a stopping device.

Furthermore, my invention includes as one of its features a series of feeding-rollers cooperative with the conveyor and serving at 45 the same time as flattening or compressing devices to unite the gummed portion of the blank with its opposite edge portion or blank side.

My invention has also for its object the improved construction of the carton-discharging

mechanism whereby the folded blanks are consecutively pushed upward against the weight of the upper pile of blanks, which serve in a measure to maintain each freshly gummed and compressed carton in perfectly flat condition, and therefore allow ample time for the gum to dry or set. 55

Further objects of the invention will be found to be carried out in the particular construction and organization of some of the co-operating elements, as will be hereinafter described, and pointed out in the claims. 60

In the accompanying drawings, in which similar characters denote similar parts, Figures 1 and 2 together illustrate a top view of 65 my improved machine. Figs. 3 and 4 together show a side view thereof, the front frame being removed. Fig. 5 is a vertical cross-section on line *a*, Fig. 4, looking in the direction of arrow 5. Fig. 5^a shows the action of the side-folders to complete the carton, and Fig. 6 is a section on line *a*, Fig. 4, looking in the direction of arrow 6 of that figure. 70

In the drawings, 10 denotes a suitable frame 75 supporting in bearings 11 the driving-shaft 12, carrying a pulley 13, to which movement may be imparted by any convenient source. Also mounted on this shaft is a bevel-gear 14, meshing with a similar gear 15, secured upon 80 a longitudinally-disposed shaft 16, which constitutes the principal driving and actuating member for various operating parts of the machine.

In order to arrive at a clear understanding 85 of my improved machine, I will describe the several parts substantially in the succession with which they operate upon the blanks, a number of which are piled up near the left end of the machine and which are fed one at 90 a time from the bottom of the pile. It is of course presupposed that the blanks are properly cut and scored—for instance, as clearly shown in Fig. 1—to be folded on the longitudinal score-lines *a* and *b* after a marginal line 95 of gum or other adhesive substance has been deposited upon the flap *c*. The blanks are piled in a magazine formed by adjustable guiding-posts 20, having slotted bases 21, which may be secured upon the frame of the ma- 100

chine by clamp-bolts 22. Referring to Figs. 3 and 5, it will be seen that the side guide-posts 20 are provided with inwardly-projecting stops or ledges 23 certain distances apart 5 vertically according to the height of said posts, and these ledges constitute one feature of my invention, as above stated, their object being to serve as intermediate supports for the blanks and to relieve the bottom blank of any excessive friction due to the weight of a great number of blanks above the same. In Fig. 5 especially the function of these ledges is clearly shown, the upper pile of blanks being sustained by their edges resting on said stops, 15 while their central portions will sag and exert but little pressure on the lower pile of blanks. Of course it is evident that as the lower pile below the pins 32 diminishes one blank at a time the upper pile above the pins 20 32 will contribute its lowest blank to the lower pile. The forward edges of the pile of blanks are supported on a roller 25, and a gage-plate 26, disposed in front of the pile, regulates the outlet-opening for what become successively 25 the bottom blanks of the pile. The rear edges of the blanks rest upon plates 27, provided with slots 28 for the adjustment of blank-engaging blocks 29 and secured upon a yoke 30, to which reciprocatory movement on stationary 30 longitudinally-disposed rods 31 may be imparted by a lever 32, fulcrumed at 33 on a bracket 34, depending from the machine-frame and having at its upper end a link connection 35 with the yoke 30, while its lower end is actuated by a pitman 36, operated by a cam 37, (see Figs. 1 and 5,) secured upon the driving-shaft 12. As the yoke 30 is moved forward by the mechanism just described the blank is engaged by a pair of superposed feed- 40 rolls 40 41, mounted on shafts 42 43, which are journaled in adjustable boxes carried by the frame 10, and one shaft, 42, is constantly driven by a sprocket 44 and chain 45, actuated by a sprocket 46, mounted on the shaft 12. 45 The roller 40 constitutes a pulley for an endless belt 47, which forms the blank receiving and transferring device proper and which also, passes over a roller 48, mounted on a shaft 49, journaled in a bearing carried by the frame 50 10. Coöoperative with the carrier-belt 47 are the roller 41, above referred to, and also a series of transfer-rollers 50, which are journaled on studs 51, held in frames 52, extending laterally of the machine and mounted on a 55 rock-shaft 53, which is journaled in brackets 54, secured to the frame. Proper oscillatory or rocking motion may be imparted to the shaft 53 by a cam 55, (see Fig. 5,) secured on the main shaft 16 and actuating through 60 a pitman 56 an arm 57, carried by said rock-shaft, so that said frames 52 may be raised, as indicated by dotted lines in that figure. As the blank is pushed forward and carried along by the belt 47 a line of gum is deposited 65 on the under side of the flap *c* by a gumming

device coöoperative with the presser-roll 58, taking its supply from the gum-box G. The blank is now carried forward by the coaction of the belt 47 and the transfer-rollers 50 until its front edge meets an obstruction in the shape of a stop 59, which is preferably secured to and operated by the movement of the rock-shaft 53, so that as the roller-frames 52 are raised just previous to the arrival of the blank in its proper position to be acted upon by the side-folding mechanism to be hereinafter described, the stop 59 is simultaneously raised, and thus arrests the blanks against progress beyond that point. 75

In order to form a firm support for the traveling belt 47 at points where the rollers 50 enter into coöperation therewith, I provide below said belt and in vertical alinement with said rollers a corresponding series of belt-supporting rolls 60, journaled in a chambered bar 61, secured with its left ends on a brace 62, extending externally of the machine, while its right end is supported on a bracket 63, carried by the frame 10.

Disposed below and above the line of travel 90 of the blank, respectively, and near the longitudinal folding-lines are one pair of blank-supporting blades 64, attached to the brace 62, above mentioned, and for preventing the blank from bending during the folding operation, and one pair of what may be termed "folding-swords" 65 65', rigidly mounted on a brace 66 and serving as edges around which the blank-flaps are folded on the score-lines *a* and *b* by the following mechanism. 95

Journaled below the blank line of travel are a pair of longitudinally-disposed shafts 70 71, having collars 72 73 for holding the folding-blades 74 75, respectively, the first-named, 74, of which folds the flap *c* around the outer edge 105 of the upper sword 65 in the manner shown in Fig. 5^a and which is operated by oscillating the shaft 70—as, for instance, shown in Fig. 6, in which said shaft is provided with a pinion 76, engaged by a rack 77, receiving proper reciprocation from a cam (not shown) on the main shaft 16. In a like manner the shaft 71 has a pinion 78, actuated by a rack 79, also operated from the main shaft 16 to fold the flap *d* around the outer edge of the sword 65' subsequently to the first folding operation, and consequently to lay the edge of the flap *d* on top of the now uppermost and gummed edge of the flap *c*, at the same time pressing the flap ends together. The blank is now practically in the form of a collapsed carton, and as the shaft 53 is now rocked to drop the stop 59 out of the path of the folded blank, at the same time again bringing the rolls 50 downward, and thus 115 forcing the carton against the traveling belt 47, the blank is withdrawn from the folding-swords 65 65' and conducted onto a stationary support consisting in the present instance of a series of laterally-disposed bars 80, having 120

130

their front edges rounded, as shown in Fig. 4, to facilitate the longitudinal movement of the carton. I preferably employ, in conjunction with the supporting-bars 80, a corresponding series of rods 81 above the carton line of travel to hold the blank on the supports 80 and guide it properly against a stop 82, adjustably held on the frame 10 to provide for different sizes of cartons.

10 Thus far the blank has been moving longitudinally of the machine, and its path is now changed into a lateral travel. The mechanism for effecting this movement comprises a pusher 90, secured to the end of a spring-actuated arm 91, which is fulcrumed at 92 and is operated by a cam 93, secured upon the shaft 16 and engaging a roller 94 on said cam. The folded blank is thereby carried between a pair of flattening-rolls 95 96, which are geared together and to which rotary movement is imparted by sprockets 97 98 and a chain 99. (See Fig. 2.) The carton, now finished, is delivered by the flattening-rolls 95 96 to a table 100, having a vertical reciprocatory movement to stack the cartons in a pile, to which each succeeding carton is added by being placed at the bottom thereof, as can be clearly seen in Fig. 6. Here the table 100 is shown carried by an arm 101, fulcrumed at 102 on the frame 10 and operated vertically by a cam 103 on the shaft 16, engaging a roller 104, journaled on the pitman 105. The lateral movement of the cartons as they are thrown upon the table is limited by a pair of posts 106, 35 and a pair of posts 107 are held on the framework of the machine to guide the blanks into a substantially even pile by serving as gage-rod for the rear edges of the cartons, and in order to permit the blanks properly to find 40 their places between the rods 106 107 the latter are beveled at 107'. (See Fig. 6.)

Pivottally secured on the posts 106 and 107 are by-pass abutments 110, the inner ends of which project into the path of the cartons and are pushed upward thereby to permit the table to rise to the limit of its movement, (see dotted lines, Fig. 6,) thereby raising the entire pile of cartons sufficiently to permit the abutments 110 to drop to their normal position again, so that when the table is now lowered all the blanks above the table will come to rest on the abutments 110 and the table will return empty to its lowermost position.

Having thus described my invention, what I claim, and desire to secure by Letters Patent, is—

1. In a paper-box machine, the combination with feeding-in mechanism for removing successive blanks from the bottom of the pile, of a folding mechanism comprising a pair of blank-side folders, an endless belt for conveying the blank to the folding mechanism, and transfer-rollers coöperative with said belt, and for conveying the blank to the folding mechanism.

2. In a paper-box machine, the combination with feeding-in mechanism for removing successive blanks from the bottom of the pile, of a folding mechanism comprising a pair of blank-side folders, an endless belt for conveying the blank to the folding mechanism, transfer-rollers coöperative with said belt, and for conveying the blank to the folding mechanism, and means for disengaging said rollers from said belt.

75

3. In a paper-box machine, the combination with feeding-in mechanism for removing successive blanks from the bottom of the pile, of a folding mechanism comprising a pair of blank-side folders, an endless belt for conveying the blank to the folding mechanism, transfer-rollers coöperative with said belt, and for conveying the blank to the folding mechanism, and an oscillatory shaft controlling the position of said rollers relative to said belt.

80

4. In a paper-box machine, the combination with feeding-in mechanism for removing successive blanks from the bottom of the pile, of a folding mechanism comprising a pair of blank-side folders, an endless belt for conveying the blank to the folding mechanism, means for actuating said belt continuously, and a stop for positioning the blank relatively to the folding mechanism.

85

5. In a paper-box machine, the combination with feeding-in mechanism for removing successive blanks from the bottom of the pile, of a folding mechanism comprising a pair of blank-side folders, an endless belt for conveying the blank to the folding mechanism, transfer-rollers coöperative with said belt, and for conveying the blank to the folding mechanism, and means for disengaging said rollers from said belt, and an oscillatory shaft controlling the position of said rollers relative to said belt, and for positioning the blank relatively to the folding mechanism.

90

100

105

6. In a paper-box machine, the combination with feeding-in mechanism for removing successive blanks from the bottom of the pile, of a folding mechanism comprising a pair of blank-side folders, an endless belt for conveying the blank to the folding mechanism, transfer-rollers coöperative with said belt, and for conveying the blank to the folding mechanism, and means for disengaging said rollers from said belt, an oscillatory shaft controlling the position of said rollers relative to said belt, and means for limiting the advance movement of the blank simultaneously.

110

115

120

7. In a paper-box machine, the combination with folding-swords for engaging the surface of the blank near the fold score-line, and a folding mechanism comprising a pair of blank-side folders, of means for withdrawing the folded blanks from said swords, and a discharge mechanism, and a device for positioning the folded blank in lateral alinement with the discharge mechanism.

125

130

8. In a paper-box machine, the combination with stationary folding-swords, and a folding mechanism comprising a pair of blank-side folders coöoperative therewith, of a discharge mechanism comprising a laterally-operated pusher, means for withdrawing the folded blank from said swords, and a device for positioning the folded blank in lateral alinement with said pusher.
9. In a paper-box machine, the combination with a folding mechanism comprising a pair of blank-side folders, and a discharge mechanism for the folded blanks, of a blank-flattening mechanism, and means for transferring the folded blank to the flattening mechanism.
10. In a paper-box machine, the combination with a folding mechanism comprising a pair of blank-side folders, and a discharge mechanism for the folded blanks, of a pair of blank-side folders, and a discharge mechanism for the folded blanks, of a blank-flattening mechanism, and means for transferring the folded blank to the flattening mechanism.
11. In a paper-box machine, the combination with a folding mechanism comprising a pair of blank-side folders, and a discharge mechanism for the folded blanks, of a pair of coöoperative flattening-rolls for the blank, and means for transferring the folded blank to the flattening-rolls.

mechanism for the folded blanks, of a blank-flattening mechanism, and a cam-operated device for transferring the folded blank to the flattening mechanism.

11. In a paper-box machine, the combination with a folding mechanism comprising a pair of blank-side folders, and a discharge mechanism for the folded blanks, of a pair of coöoperative flattening-rolls for the blank, and means for transferring the folded blank to the flattening-rolls.

Signed by me at Springfield, Massachusetts, in presence of two subscribing witnesses.
